United States Patent Office.

WILLIAM ZIOCK, OF SAINT LOUIS, MISSOURI.

Design No. 2,774, dated August 27, 1867.

DESIGN FOR A TRADE-MARK.

The Schedule referred to in these Letters Patent and making part of the same.

TO ALL WHOM IT MAY CONCERN:

Be it known that I, WILLIAM ZIOCK, of the city and county of Saint Louis, State of Missouri, have invented and produced a new Design for a Trade-Mark, of which the following is a full, clear, and exact description, reference being had to the drawing annexed hereto, making a part of this specification.

My design consists of eight spools, connected by threads of yarn in the manner substantially as shown in the drawing, in combination with the words "Manchester Knitting-Yarn." The words "knitting yarn," being in rustic letters, as shown.

This design is intended to be used either as a brand or as an engraving, and when used as the former the various parts will have such breaks in them as may be necessary to give the requisite strength to the stencil or other plate by which the impression is made.

What I claim as my invention, and desire to secure by Letters Patent, is—

The design for a trade-mark, substantially as shown and specified.

WM. ZIOCK.
